PAPER AND DEODORANT DISPENSER

Filed April 7, 1947

UNITED STATES PATENT OFFICE

2,546,820

PAPER AND DEODORANT DISPENSER

Philip J. Grant, Oakland, Calif.

Application April 7, 1947, Serial No. 739,939

3 Claims. (Cl. 242—55.2)

1

This invention relates to and in general has for its object the provision of a combination paper and deodorant dispenser, and more particularly a dispenser for dispensing a deodorant and toilet tissue in roll form.

A further object of the invention is the provision of a dispenser for the purpose described, wherein a hollow roll serves as a spool for supporting a roll of tissue and for accommodating a deodorant either in powder or liquid form, and wherein means is provided for readily removing the roll from its mountings for applying thereto either a refill of paper or deodorant.

The invention possesses other advantageous features, some of which with the foregoing will be set forth at length in the following description where that form of the invention which has been selected for illustration in the drawings accompanying and forming a part of the present specification is outlined in full. In said drawings, one form of the invention is shown, but it is to be understood that it is not limited to such form, since the invention as set forth in the claims may be embodied in a plurality of forms.

Referring to the drawings:

Fig. 1 is an isometric projection of a paper and deodorant dispenser embodying the objects of my invention.

Fig. 2 is an exploded, isometric projection of the hollow deodorant receptacle and paper roll supporting member shown in Fig. 1.

Fig. 3 is a reduced longitudinal vertical section taken on the line 3—3 of Fig. 1.

As shown in Fig. 1, my dispenser includes a semi-cylindrical metal shell 1 bounded by a frame 2 and arranged to be recessed within a bathroom or lavatory wall 3, all in accordance with well known practice.

Extending outwardly from each of the vertical side members 4 and 5 of the frame 2 and forming a continuation of end walls of said shell are bearing brackets 6 and 7, respectively formed on their inner faces with circular recesses 8 and 9. As shown in Fig. 3, the bracket 7 is formed with a circular opening 11 and with a counterbore 12 coaxial therewith and in open communication with the recess 9.

Disposed between the bearing brackets 6 and 7 is a transparent plastic cylinder or mandrel 13 provided at each end with longitudinally extending, diametrically opposed slots 14. Force fitted over the ends of the cylinder 13 are opposed metal caps 15 and 16 provided with perforations 17 for establishing communication between the interior and exterior of the cylinder. The function of

the slots 14 is simply to permit the ends of the cylinder to flex sufficiently to permit the mounting and removal of the caps 15 and 16. Riveted to the cap 15 coaxially therewith is an outwardly extending pin 18, and fastened thereto by a set screw 19 is a disc bearing or stub bearing shaft 21 journaled in the recess 8.

Fastened to the cap 16 coaxially therewith is a closed ended metal sleeve or cylinder 22 provided on one side with a longitudinally extending slot 23. Telescopically associated with the cylinder 22 is closed ended cylinder 24, provided on its inner end with a finger or stop 25 bent outwardly through the slot 23 so as to limit the outward movement of the cylinder 24 relative to the cylinder 23. Disposed within telescoping cylinders is a coil spring 26 serving to resiliently urge the outer cylinder 24 in its extended position. Mounted on the outer end of the cylinder 24, by a set screw 27, is a disc bearing 28 journaled in the bearing recess 9. Fastened to the cylinder 24 by a set screw 29 is a stop 31 preferably in the form of a ring or disc. The screw 29 is provided with a hexagonal recess in its head rather than a conventional kerf and consequently can be loosened only by a special screw driver having a head designed to fit it.

Extending through the opening 11 is a pin 32 and threaded to the inner end thereof is a ring 33 held within the counterbore 12 by the outer spring retaining cylinder 24. The outer end of the pin 32 is formed with a flange or button 34 which when depressed serves to release the disc bearing 28 from its bearing 9 provided that the stop disc 31 is either loose on the cylinder 24 or locked thereon against the disc bearing 28. In this connection, it should be noted that the distance between the bracket 7 and the cap 16 should be slightly greater than the width of the disc bearing 28 plus the width of the stop disc 31 so that when the stop disc 31 is locked to the cylinder 24, against the disc bearing 28, the latter may still be made to clear the bracket 7 by depressing the button 34. By locking the stop disc 31 midway between the bracket 7 and the cap 16, as shown in Fig. 3, it becomes impossible to remove the cylinder 13 and consequently the roll 35 of tissue which is mounted on it.

To load the cylinder 13 with paper and a deodorant, it is first removed from the brackets 6 and 7 by depressing the button 34 as above indicated. One of the caps 15 or 16 is then removed and a deodorant 36 either in powder form or in the form of a solution impregnated in a suitable wick is introduced into the cylinder.

This having been done, the cap is replaced and a roll of tissue is threaded on the cylinder. To mount the cylinder 13 in the brackets 6 and 7 in its operative position, the disc bearing 21 is inserted into the bearing recess 8 and the opposed disc bearing 28 is depressed against the action of the spring 26 until it clears the inner face of the bracket 7 and can be allowed to snap into its bearing recess 9 as shown in Figs. 1 and 3. If it is then desired to make the device tamper proof, the stop disc 31 is locked in the position shown in Fig. 3 as previously explained.

If deodorant 36 be of the absorbent type, it will absorb any odors within the immediate vicinity of the device and which are permitted to pass through the perforations 17. If the deodorant be of the vaporizing type, it will emit counteracting vapors through the perforations 17 to the surrounding atmosphere. Since the cylinder 13 is transparent, it is easy to determine whether a recharge of deodorant is necessary.

Having thus described my invention, what I claim and desire to secure by Letters Patent is:

1. A rolled-paper dispenser comprising: a hollow mandrel provided at one end with a stub bearing shaft; a cap detachably secured over the opposite end of said mandrel; an inwardly extending sleeve fixed to said cap coaxially therewith; an outwardly extending sleeve arranged to telescope within said inwardly extending sleeve; a loading spring disposed within said sleeves and arranged to resiliently urge said sleeves apart; a disc bearing mounted on the outer end of said outwardly extending sleeve; a stop mounted on said outwardly extending sleeve intermediate its ends, and means for locking said stop to said sleeve.

2. A rolled-paper dispenser comprising: a hol-

low mandrel; a cap detachably secured over each end of said mandrel, one of said caps being apertured; a disc bearing secured to one of said caps coaxially therewith; an inwardly extending sleeve secured to the other of said caps coaxially therewith; an outwardly extending sleeve telescoping with said inwardly extending sleeve; a loading spring disposed within said sleeves for resiliently urging them apart, and a disc bearing secured to the outer end of said outwardly extending sleeve.

3. A rolled-paper dispenser comprising: a hollow mandrel; a cap detachably secured over each end of said mandrel, one of said caps being apertured; a disc bearing secured to one of said caps coaxially therewith; an inwardly extending sleeve secured to the other of said caps coaxially therewith; an outwardly extending sleeve telescoping with said inwardly extending sleeve; a loading spring disposed within said sleeves for resiliently urging them apart; a disc bearing secured to the outer end of said outwardly extending sleeve; a stop ring mounted on said outer sleeve intermediate its ends, and means for locking said ring to said sleeve.
